EXEMPLARY CLAIM

1. A compound selected from the class consisting of

wherein R' is an alkyl group containing not more than three carbon atoms, R'' is selected from the class consisting of open chain alkyl groups containing not more than eight carbon atoms, the cyclohexyl group, and alkyl cyclohexyl groups containing not more than 16 carbon atoms, R''' is an alkyl group containing not more than eight carbon atoms, and X⁻ is selected from the class consisting of chloride, bromide and iodide.

14 Claims, No Drawings

3-PYRIDYL PHOSPHONATES

The invention described herein may be manufactured and used by or for the Government of the United States of America for governmental purposes without the payment to us of any royalty thereon.

This is a continuation-in-part of application Ser. No. 564,584, filed Feb. 9, 1956 and now abandoned.

This invention relates to 3-pyridyl phosphonates and quaternary salts thereof. It also relates to a process for manufacturing these compounds.

The new compounds of the present invention may be represented by the following general formulas:

wherein R' is an open chain alkyl group which contain not more than 3 carbon atoms, R'' is an open chain alkyl group containing not more than 8 carbon atoms, a cyclohexyl group, or an alkyl-cyclohexyl group containing not more than 16 carbon atoms, R''' is an alkyl group containing not more than 8 carbon atoms, and X⁻ is chloride, bromide or iodide.

These compounds are useful as chemical warfare agents. They have an extremely high anticholinesterase activity and a mammalian toxicity of an entirely different magnitude than superficially similar compounds such as the 3-pyridyl dialkyl phosphates disclosed in British Pat. No. 666,596. The compounds of the British Patent differ from those claimed herein in that R' in the above structural formulae is an alkoxy group rather than the alkyl group of our compounds. The mammalian toxicity of the phosphates is not sufficiently high to make them useful for our purposes.

Our compounds may be utilized in any munitions suitable for handling a relatively non-volatile toxic agent, such as bombs, shells, spray tanks, aerosol generators, etc.

The present invention also includes a process for the manufacture of 3-pyridyl phosphonates of the above general formula I by reacting on alkali metal derivative of 3-pyridol, having the formula

with an alkyl or cycloalkyl alkylphosphonhalide having the formula

In these formulae M represents an alkali metal, preferably sodium or potassium, X represents halogen, preferably chlorine, and R' and R'' have the same meaning as in general formulas I and II. The reaction may best be conducted in solution or suspension in an anhydrous inert solvent such as, for example, absolute ethyl alco-

hol or other anhydrous alcohols, or a hydrocarbon, e.g., benzene, xylene or a petroleum fraction. The reaction is exothermic and should be carried out with cooling.

The invention also includes a second, but closely related, process for the manufacture of the 3-pyridyl phosphonates. According to this modification, 3-pyridol itself is reacted with the alkyl or cycloalkyl alkylphosphonohalide, preferably in a hydrocarbon solvent such as benzene, xylene, or a petroleum fraction, in the presence of an amine-type HCl acceptor, for example triethylamine, other trialkyl amines, pyridine, diethyl aniline, or other tertiary amines.

The resulting alkyl 3-pyridyl alkylphosphonates may be converted to the quaternary salts of general formula II by the usual methods employed for producing quaternary pyridinium compounds, e.g. by reaction with the proper alkyl halide. The quaternary salts are water soluble and in some cases may be preferred for that reason.

Examples of preferred alkyl alkylphosphonohalides employed as reactants are:

Ethyl methylphosphonochloride

Isopropyl methylphosphonochloride

Cyclohexyl methylphosphonochloride

3-Methylcyclohexyl methylphosphonochloride

3,3,5-Trimethylcyclohexyl methylphosphonochloride

(Derived from the low-melting isomer of 3,3,5-trimethyl cyclohexanol)

These intermediates have been prepared according to the general reaction.

The procedure employed in each case was as follows: The methylphosphonic dichloride and triethylamine, 2 percent excess of each, were dissolved in 125 ml. of n-hexane (0.5 mole run). The alcohol, R'' OH, 0.5 mole previously dissolved in 75 ml of dry hexane, was then added dropwise with stirring and cooling during a 15 min. period at a reaction temperature of 10° to 15°C. The reaction mixture was then allowed to warm to room temperature and finally heated to 40°-45° C for 1 hour.

In some cases the resulting solution was used directly in the main reaction. In others the triethylamine hydrochloride was removed by filtration and the filtrate was distilled. After stripping of the hexane, the last traces under a vacuum (2mm Hg., abs.), the phosphonochloride was obtained in good yield and adequate purity for use in the main reaction for the preparation of our novel compounds.

The following examples illustrate how the process of the invention may be carried into effect:

EXAMPLE 1

3-Methylcyclohexyl 3-pyridyl methylphosphonate

An ethanolic solution of the sodium salt of 3-pyridol was prepared by adding 3-pyridol (9.5 g., 0.1 M) to a solution of sodium ethoxide, made by dissolving metal-

lic sodium (2.3 g., 0.1 M) in absolute ethanol (100 ml.). 3-Methylcyclohexyl methylphosphonochloridate (21.1 g., 0.1 M) was added over a period of 5 minutes while stirring and cooling. The reaction temperature was maintained at 35°C., and the mixture allowed to stir for an additional 1½ hours at 30°C. The solvent was then distilled off at reduced pressure and the residual oil dissolved in xylene (50 ml.). It was then washed with 5 percent sodium hydroxide solution (6 × 85 ml.), 5 percent sodium chloride solution (2 × 85 ml.) and water (2 × 85 ml.). After removal of the solvent at reduced pressure the product was evacuated to 2 mm. Hg. at 50°–55°C. for 3 hours. The unvaporized material constituted the product. The yield was 14.5 g. (=54 percent).

EXAMPLE 2

3,3,5-Trimethylcyclohexyl 3-Pyridyl Methylphosphonate

This compound was prepared in a manner similar to that of Example 1 from 3-pyridol (23.8 g., 0.25), sodium (5.75 g., 0.25 M), absolute ethanol (200 ml.) and 3,3,5-trimethylcyclohexyl methylphosphonochloridate (59.7 g., 0.25 M). The yield was 55.6 g. (=74.8%).

Instead of employing the alkali metal salt of pyridol, pyridol itself may be used as the reactant, the reaction being carried out in the presence of an amine type HCl acceptor, preferably triethylamine. The following example shows a typical preparation of a compound by this method.

EXAMPLE 3

3,3,5-Trimethylcyclohexyl 3-Pyridyl Methylphosphonate

Methylphosphonic dichloride (33.2 g., 0.25 M) and triethylamine (25.3 g., 0.25 M) were dissolved in 200 ml. of benzene and the low melting isomer of 3,3,5-trimethylcyclohexanol (35.5 g., 0.25 M) was added slowly while stirring and cooling. A reaction temperature of 10°–15°C. was maintained. It was then heated to 40°C. for an additional hour. This mixture is now essentially a benzene solution of 3,3,5-trimethylcyclohexyl methylphosphonochloridate. Triethylamine (25.3 g., 0.25 M) was again added to the reaction mixture and 3-pyridol (23.8 g., 0.25 M) was added slowly while stirring and cooling. A reaction temperature of 35°C. was maintained. After stirring for an additional hour at room temperature the mixture was washed with 5 percent sodium hydroxide solution (5 × 100 ml.) followed by water (3 × 100 ml.). The solvent was then removed by distillation at reduced pressure. A yield of 66.0 g. (=88.8 percent) of product remained.

It will be noted that in Example 3, the low melting isomer of 3,3,5-trimethylcyclohexanol was used as the starting material. We have also carried out the same preparation using the high melting isomer, but find that the compound produced is much less toxic than that derived from the low-melting isomer. The differences in structure in the final compounds which are responsible for these differences in toxicity are not known to us. Accordingly we designate the compound of Example 3 simply as "3,3,5-trimethylcyclohexyl 3-pyridyl methylphosphonate derived from the low-melting isomer of 3,3,5-trimethylcyclohexanol."

EXAMPLE 4

Isopropyl 3-Pyridyl Methylphosphonate

Sodium metal (4.6 g.) was dissolved in 100 ml. of absolute ethanol and 3-pyridol (19.0 g.) was added. Isopropyl methylphosphonochloridate (31.3 g.) was then added dropwise while the mixture was stirred. An exothermic reaction occurred and cooling was necessary to maintain the reaction temperature at 30°–35°. The mixture was refluxed for 1 hr., filtered and distilled. A yield of 27 g. (63 percent) of product was obtained boiling at 72°/1mm. Anal. called for, $C_9H_{14}NO_3P$: C, 50.2; H, 6.6; N, 6.5; P, 14.4; Found: C, 50.1; H, 6.4; N, 6.4; P, 14.3.

EXAMPLE 5

Cyclohexyl 3-Pyridyl Methylphosphonate

Sodium metal (5.75 g., 0.25 mole) was dissolved in 200 ml. of absolute ethanol and 3-pyridol (23.8 g., 0.25 mole) was added. After stirring at room temp. for 1 hr., cyclohexyl methylphosphonochloridate (49.2 g., 0.25 mole) was added slowly while the mixture was stirred. An exothermic reaction occurred and cooling was necessary to maintain the reaction temp. at 35°. After stirring for an additional 2 hrs and standing overnight, the solvent was stripped off at reduced pressure. The residue was dissolved in a mixture containing 100 ml. of xylene and 100 ml. of 5% NaOH solution. The xylene solution containing the desired product was then washed with 5% NaOH solution (5 × 200 ml.) and an equal amount of water. The solvent was stripped off at reduced pressure and the residue was submitted for analysis.

A yield of 31.4 g. (46.6 percent) was obtained. Anal. Calcd. for $C_{13}H_{20}NO_3P$: C, 58.9; H, 7.5; N, 5.2; P, 11.5. Found: C, 58.2; H, 7.5; N, 4.8; P, 11.5.

EXAMPLE 6

Methyl 3-Pyridyl Methylphosphonate

Equimolar quantities of methyl methylphosphonochloridate and triethylamine are dissolved in xylene. An equimolar quantity of 3-pyridol in xylene is slowly added with constant stirring and cooling. The mixture is stirred for an additional hour. A reaction temperature of about 30°C is maintained by cooling. The reaction mixture is then treated in the same manner as given in Example 3.

EXAMPLE 7

Ethyl 3-Pyridyl Methylphosphonate

Metallic sodium is dissolved in absolute ethanol to form a solution of sodium ethoxide. 3-Pyridol is then added slowly at a temperature of 50°C. with good stirring. Ethyl methylphosphonochloridate is then added slowly with continuous stirring and cooling, a temperature of about 30°C. being maintained. Stirring is continued for an additional hour at the same temperature. The reaction product is then treated in the same manner as Example 1.

EXAMPLE 8

n-Octyl 3-Pyridyl Methylphosphonate

Equimolar quantities of n-octyl methylphosphonochloridate and triethylamine are dissolved in benzene. An equimolar quantity of 3-pyridol is then added

slowly with constant stirring and cooling to about 30°C. The mixture is then stirred for an additional hour at the same temperature and the product is recovered in the manner set out in Example 3, above.

EXAMPLE 9

Diisopropylcarbiny 3-Pyridyl Methylphosphonate

Equimolar quantities of diisopropylcarbiny methylphosphonochloride and triethylamine are dissolved in benzene. An equimolar quantity of 3-pyridol is then added slowly with constant stirring, the temperature being maintained at about 30°C. The mixture is then stirred for an additional hour at the same temperature and the product is recovered in the manner set out in Example 3.

EXAMPLE 10

Ethyl 3-Pyridyl Ethylphosphonate

Equimolar quantities of ethyl ethylphosphonochloride and triethylamine are dissolved in benzene. An equimolar quantity of 3-pyridol is added slowly with constant stirring. The temperature is maintained at about 35°C. by cooling. After all the pyridol has been added, the mixture is stirred at room temperature for another hour. The product is then separated in the manner given in Example 3.

EXAMPLE 11

Cyclohexyl 3-Pyridyl Ethylphosphonate

Equimolar quantities of cyclohexyl ethylphosphonochloride and triethylamine are dissolved in benzene. An equimolar quantity of 3-pyridol is then added slowly with constant stirring. The temperature is maintained at about 30°C. by cooling. After all the pyridol has been added the stirring is continued for an additional hour at room temperature.

The product is recovered as set out in Example 3.

The compounds of our general formula I are easily converted to the quaternary compounds of general formula II by simply adding the proper alkyl halide, preferably in excess, to a hydrocarbon solution of the pyridyl phosphonate. The quaternary compounds are insoluble in and of higher density than the hydrocarbon and settle out, forming a layer which is readily separated. When R''' is methyl we prefer, under laboratory conditions, to use methyl iodide as the halide, because of the very low boiling point of the chloride and bromide. Methyl bromide or methyl chloride may, however, be utilized by carrying out the reaction in an autoclave. For higher members, the cheaper chlorides or bromides may conveniently be used.

EXAMPLE 12

2-Methylcyclohexyl 3-Pyridyl Methylphosphonate Methiodide

Fifteen grams of 2-methylcyclohexyl 3-pyridyl methylphosphonate was dissolved in 75 ml. of dry benzene, and 30 ml. of methyl iodide was added. After standing overnight, a benzene-insoluble layer was formed which was removed and washed three times with dry benzene. To remove the last trace of benzene, the product was evacuated to 2 mm. Hg at 45° for 3 hrs. The product on analysis was found to contain 28.3 percent iodine, (theoretical-30.86 percent).

EXAMPLE 13

3,3,5-Trimethylcyclohexyl 3-Pyridyl Methylphosphonate Methiodide

5 The procedure of Example 12 was repeated exactly, except that 3,3,5-trimethylcyclohexyl 3-pyridyl methylphosphonate was used as the reactant. The product was an oil containing by analysis 30.97 percent iodine (theoretical, 28.89 percent).

EXAMPLE 14

3,3,5-Trimethylcyclohexyl 3-Pyridyl Methylphosphonate Ethobromide

10 Fifteen grams of 3,3,5-trimethylcyclohexyl 3-pyridyl methylphosphonate is dissolved in a 75 ml. benzene and 30 ml. of ethyl bromide added. The mixture is then treated in the same manner as given in Example 12.

EXAMPLE 15

Isopropyl 3-Pyridyl Methylphosphonate Butochloride

15 Fifteen grams of isopropyl 3-pyridyl methylphosphonate is dissolved in 75 ml. of benzene and 30 ml. of n-butyl chloride is added. The mixture is then treated in the same manner as given in Example 12.

20 The other compounds of our invention may be prepared by the same methods simply substituting the proper alkyl alkylphosphonohalide and, in the case of the quaternary compounds, the proper alkyl halide.

25 We have found that the identity of the alkyl groups, particularly R'', has a marked influence on the toxicity of the compounds. Particularly outstanding results are secured when R' is methyl and R'' is cyclohexyl or substituted cyclohexyl. The presence of substituents in the cyclohexyl ring further effects the toxicity. In compounds of the formula

30 the variation of toxicity with various cyclohexyl radicals as R'' was found to be as follows:

R''	Increasing Toxicity
Cyclohexyl	
4-Methylcyclohexyl	
2-Methylcyclohexyl	
3-Methylcyclohexyl	
3,3,5-Trimethylcyclohexyl	Maximum
(from the low melting isomer of 3,3,5-trimethylcyclohexanol)	
4-Cyclohexylcyclohexyl	

35 Increasing the number of carbon atoms in R' progressively lowers the toxicity. When R'' is alkyl, the same general effect is observed, but the cyclohexyl and alkyl substituted cyclohexyl groups impart a much higher toxicity than any of the alkyl groups.

40 It will be understood that the compounds shown in the Examples are merely exemplary, and that various changes are possible in the specific manner of preparing them. We therefore wish our invention to be limited solely by the scope of the appended claims.

45 We claim:

1. A compound selected from the class consisting of

wherein R' is an alkyl group containing not more than three carbon atoms, R'' is selected from the class consisting of open chain alkyl groups containing not more than eight carbon atoms, the cyclohexyl group, and alkyl cyclohexyl groups containing not more than 16 carbon atoms, R''' is an alkyl group containing not more than eight carbon atoms, and X⁻ is selected from the class consisting of chloride, bromide and iodide.

2. Cyclohexyl 3-pyridyl methylphosphonate.

3. 3-Methylcyclohexyl 3-pyridyl methylphosphonate. 20

4. 4-Methylcyclohexyl 3-pyridyl methylphosphonate.

5. 3,3,5-Trimethylcyclohexyl 3-pyridyl methylphosphonate.

6. Isopropyl 3-pyridyl methylphosphonate.

7. 2-Methylcyclohexyl 3-pyridyl methylphosphonate 25 methiodide.

8. 3,3,5-Trimethylcyclohexyl 3-pyridyl methylphosphonate methiodide.

9. A process for preparing a pyridyl alkylphosphonate of the formula

which comprises mixing an alkylphosphonochloride of the formula

in an inert solvent with a compound selected from the class consisting of 3-pyridol and its sodium and potassium salts, R' in the above formulas being an alkyl group containing not more than three carbon atoms and R'' being selected from the class consisting of open chain alkyl groups containing not more than eight carbon atoms, the cyclohexyl group, and alkyl substituted cyclohexyl groups containing not more than sixteen carbon atoms, while cooling the resulting mixture.

5 10. A process as defined in claim 9 which comprises mixing said phosphonochloride with at least one of said salts of 3-pyridol in solution in anhydrous alcohol.

15 11. A process as defined in claim 9 which comprises mixing said alkylphosphonochloride with pyridol in a hydrocarbon solution in the presence of a tertiary amine.

12. A process as defined in claim 11 wherein said amine is triethylamine.

13. 3,3,5-Trimethylcyclohexyl 3-pyridyl methylphosphonate derived from the low melting isomer of 3,3,5-trimethyl cyclohexanol by mixing said 3,3,5-trimethylcyclohexanol with methylphosphonic dichloride in an inert solvent in the presence of a tertiary amine HCl acceptor while cooling said mixture, thereafter heating said mixture to a temperature of about 40° C, and adding 3-pyridol to said mixture in the presence of a tertiary amine HCl acceptor while stirring and cooling said mixture.

30 14. The process of preparing 3,3,5-trimethylcyclohexyl 3-pyridyl methylphosphonate consisting essentially of mixing the low-melting isomer of 3,3,5-trimethylcyclohexanol with methylphosphonic dichloride in an inert solvent in the presence of a tertiary amine HCl acceptor while cooling said mixture, thereafter heating said mixture to a temperature of about 40°C, and adding 3-pyridol to said mixture in the presence of a tertiary amine HCl acceptor while stirring and cooling said mixture.

40 15. A process for preparing 3,3,5-trimethylcyclohexyl 3-pyridyl methylphosphonate consisting essentially of mixing the low-melting isomer of 3,3,5-trimethylcyclohexanol with methylphosphonic dichloride in an inert solvent in the presence of a tertiary amine HCl acceptor while cooling said mixture, thereafter heating said mixture to a temperature of about 40°C, and adding 3-pyridol to said mixture in the presence of a tertiary amine HCl acceptor while stirring and cooling said mixture.

45 16. A process for preparing 3,3,5-trimethylcyclohexyl 3-pyridyl methylphosphonate consisting essentially of mixing the low-melting isomer of 3,3,5-trimethylcyclohexanol with methylphosphonic dichloride in an inert solvent in the presence of a tertiary amine HCl acceptor while cooling said mixture, thereafter heating said mixture to a temperature of about 40°C, and adding 3-pyridol to said mixture in the presence of a tertiary amine HCl acceptor while stirring and cooling said mixture.

50 17. A process for preparing 3,3,5-trimethylcyclohexyl 3-pyridyl methylphosphonate consisting essentially of mixing the low-melting isomer of 3,3,5-trimethylcyclohexanol with methylphosphonic dichloride in an inert solvent in the presence of a tertiary amine HCl acceptor while cooling said mixture, thereafter heating said mixture to a temperature of about 40°C, and adding 3-pyridol to said mixture in the presence of a tertiary amine HCl acceptor while stirring and cooling said mixture.

55 18. A process for preparing 3,3,5-trimethylcyclohexyl 3-pyridyl methylphosphonate consisting essentially of mixing the low-melting isomer of 3,3,5-trimethylcyclohexanol with methylphosphonic dichloride in an inert solvent in the presence of a tertiary amine HCl acceptor while cooling said mixture, thereafter heating said mixture to a temperature of about 40°C, and adding 3-pyridol to said mixture in the presence of a tertiary amine HCl acceptor while stirring and cooling said mixture.

60 19. A process for preparing 3,3,5-trimethylcyclohexyl 3-pyridyl methylphosphonate consisting essentially of mixing the low-melting isomer of 3,3,5-trimethylcyclohexanol with methylphosphonic dichloride in an inert solvent in the presence of a tertiary amine HCl acceptor while cooling said mixture, thereafter heating said mixture to a temperature of about 40°C, and adding 3-pyridol to said mixture in the presence of a tertiary amine HCl acceptor while stirring and cooling said mixture.

65 20. A process for preparing 3,3,5-trimethylcyclohexyl 3-pyridyl methylphosphonate consisting essentially of mixing the low-melting isomer of 3,3,5-trimethylcyclohexanol with methylphosphonic dichloride in an inert solvent in the presence of a tertiary amine HCl acceptor while cooling said mixture, thereafter heating said mixture to a temperature of about 40°C, and adding 3-pyridol to said mixture in the presence of a tertiary amine HCl acceptor while stirring and cooling said mixture.
